MANUFACTURE OF FABRICS

James Morton, Carlisle, England

Application June 19, 1933, Serial No. 675,185
In Great Britain June 25, 1932

30 Claims. (CL 66—85)

This invention relates to the manufacture of carpets, rugs and other fabrics of the kind including or consisting of a structure composed of warps and wefts which are not interwoven but bound together by stitching formed by knitting action.

The chief object of the invention is to make provision whereby such fabrics can be produced at a high knitting speed and with considerable structural compactness comparable with that obtained by weaving operations.

According to the invention, the fabric structure is manufactured by supplying wefts to the opposite faces, or sides, of a web, or sheet, of warps and inter-binding the said wefts by chains of stitches extending along spaces between the warps; that is, the chains are independent of one another.

The chains of stitches are each composed of two threads, yarns, or the like looped together by the same knitting needle to form the chain, the arrangement being such that each stitch consists of a loop in one thread drawn through a loop in the other, so that the loops in the respective threads alternate and interlock throughout the length of the chain, thus preventing unravelling. Provision is made for positively drawing the stitches tight at timed intervals in the cycle of operations in order to ensure that the fabric structure will be firmly consolidated, the timing being such that the knitting threads are drawn tight when they are clear of the knitting needles.

Thus, the fabric structure is tightly consolidated, and the fact that the binding threads for the time being on the knitting needles take no part in the tightening action ensures that the work performed by the knitting mechanism is not rendered any heavier and that a high knitting speed can therefore be maintained. Moreover, the fact that the chains are independent avoids the distortion which would occur if they were interconnected, and the fact that they are composed of two threads alternately acted upon by the knitting needles ensures that the chains will not unravel if a thread breaks.

The invention is especially suitable for application to the manufacture of pile fabrics, either cut or looped, and, when so applied, the aforesaid fabric structure may constitute the ground structure of the fabric. Pile warps (preferably associated with stuffer warps) extending between the independent chains of stitches are formed by hooks into pile loops, either cut or not, projecting from between the front wefts and bound into the fabric thereby.

In the manufacture of a pile fabric as aforesaid, the fact that the looping is performed by hooks, and not by the knitting-needles themselves, coupled with the fact that the pile loops are bound in place by the front wefts and not by knitting into the structure of the fabric, ensures that the pile formation does not add to the work of the knitting mechanism and therefore does not affect the knitting speed.

The knitting needles may have shanks terminating in hooks and channels wherein work tongues serving to guide the loops past the hooks during casting-off, the needles and tongues, respectively, being secured to independently actuated supports working in timed relationship.

The manufacture of pile fabrics is carried out by a machine capable of performing two successive operations during each complete cycle of operations, the one operation being a stitching operation and the other a pile-lapping operation.

For the manufacture of cut-pile fabrics the machine employed may have stationary pile-forming hooks associated with sliding knives for cutting the pile. These knives can be operated in sequence, the operation of the knives taking place continuously throughout the complete cycle.

Substantially stationary pile-forming hooks may also be employed when manufacturing uncut loop pile fabrics, but, in this case, the hooks are "floating", being supported by previously formed loops. Means are also provided to position the hooks for the pile-lapping operations.

The warps may be supplied from one or more beams; for instance, there may be a beam of stuffer warps and one or more beams of pile warps. The pile warps pass through one or more sets of guides, preferably tubes, and these guides are operated to lap the pile warps around the hooks. Especially where there are two or more sets of guides, their operation may be controlled by pattern-chains or other selecting mechanism.

Successive lengths of wefts are fed from separate supplies to opposite faces of the web or sheet of stuffer warps, and any suitable known mechanism may be employed for the purpose of placing the said lengths across said web or sheet.

The invention will now be described, by way of example, with reference to the accompanying drawings, in which:—

Fig. 1 is a diagrammatic sectional elevation of a machine for manufacturing cut pile fabrics, parts of the machine being omitted for clearness.

Fig. 2 is an elevation in the direction of the arrow II in Fig. 1, the middle parts of the machine being broken away.

Fig. 3 is a fragmentary elevation in the direction of the arrow III in Fig. 2.

Fig. 4 is a sectional elevation drawn to a large scale to show with greater clearness certain of the parts included in Fig. 1. Fig. 4 is confined mainly to the parts which act directly on the various threads and yarns of which the fabric is composed.

Fig. 5 is a fragmentary elevation showing 10 weft-supplying mechanism, this view being to a larger scale than Fig. 1 and being obtained by looking on the machine in the direction of the aforesaid arrow II in Fig. 1.

Fig. 6 is an elevation of pile-cutting mechanism.

Fig. 7 is a view drawn to a larger scale than Fig. 6 and showing with greater clearness certain of the parts included therein.

Fig. 8 is a sectional elevation corresponding to 20 Fig. 7.

Fig. 9 is a plan of certain of the parts included in Fig. 4.

Fig. 10 is a diagram illustrating a cut-pile fabric such as made by the machine illustrated 25 in Figs. 1 to 9.

Fig. 11 is a sectional elevation of a portion of a machine for manufacturing looped pile fabrics.

Figs. 12 and 13 are views showing with greater 30 clearness certain of the parts included in Fig. 11 and illustrating the loop-forming operation.

Fig. 14 is an elevation of a portion of a comb 35 positioning floating loop-forming hooks one of which is shown in Figs. 11 to 14.

Fig. 15 is an elevation of a portion of a so-called 35 cradle for supporting the floating hooks at the commencement of fabric-production.

Fig. 16 is a section on the line XVI—XVI of Fig. 15.

Fig. 17 is a section corresponding to Fig. 16, but 40 showing a floating hook in place in the cradle.

Referring firstly to the machine illustrated in Figs. 1 to 9, the working parts of this machine are supported by a stationary frame-work comprising mainly two side frames or gables 18 and 19.

45 The working parts derive their motion from a main driving shaft 20 borne by the frames 18 and 19 and rotated by any suitable external power means. The various motions are mainly derived from cams, certain of which are secured to the 50 main shaft 20 and certain others of which are secured to shafts driven either directly or indirectly by the shaft 20. These other shafts, which are shown chiefly in Figs. 1 to 3, comprise the following, namely:—

55 A half-speed cam-shaft 21 supported by the frame 18 and fixtures thereon and driven at half the speed of the shaft 20 through the intermediary of a train of gear-wheels 22. A vertical half-speed shaft 23 supported by the frame 19 and fixtures thereon and driven at half the speed of the main shaft 20 by bevel-gear-wheels 24.

60 A shaft 25, which may be termed a pattern-shaft, supported by fixtures on the frame 19 and driven at half the speed of the main shaft 20 by intermeshing spiral gear-wheels 26 on the shafts 23 and 25 respectively. A shaft 27 supported upon both frames 18 and 19 and driven at half the speed of the main shaft 20 by bevel-gear-wheels 28 on the shafts 23 and 27 respectively.

70 The machine also includes a take-up shaft 29, which is supported by both frames 18 and 19 and receives a slow intermittent rotational movement from the half-speed vertical shaft 23 through the intermediary of a single-toothed driver 30 (Figs. 2 and 3) secured to the shaft 23, a toothed

wheel 31 borne by the frame 19 and intermittently rotated by the driver 30, a gear-wheel 32 on the same shaft 33 as the toothed wheel 31, and a train of intermediate gear-wheels 34, 35 and 36 which drive a gear-wheel 37 secured to the take-up shaft 29. The gear-wheels 34, 35 are secured together and are adjustably mounted on an arm 38 which is adjustable around the axis of the shaft 33, and the gear wheel 36 is adjustably mounted on an arm 39 which is adjustable around the axis of the take-up shaft 29. The parts 32 to 37 constitute a known kind of change-speed gear, any desired change in the gear ratio being obtainable by substituting differently sized intermediate wheels in place of the gear-wheels 15 34, 35 and 36. Accordingly, the take-up shaft 29 can be driven at any desired slow intermittent rotational speed.

The yarns and threads acted upon by the machine parts to form the required cut pile fabric 20 are shown in Figs. 1 and 4 and they comprise stuffer warps A, pile warps B, C, wefts D, E and stitching threads F, G, the fabric itself being shown conventionally and being denoted by H.

The stuffer warps A are led in a single web or 25 sheet from an overhead beam 40 journalled at its ends in the frames 18 and 19. The warps A pass over a guide beam 41 directly to a part 42, which may be termed the breast-beam of the machine, without being acted upon by any of the 30 operative parts thereof; that is to say, the stuffer warps pass idly into the body of the fabric H.

The pile warps B, C are supplied as separate 35 webs or sheets from overhead beams 43 and 44 journalled at their ends in the frames 18 and 19, 35 and the warps B, C are led to a pair of guide beams 45, 46 whence they pass to two rows of guide-tubes 47 and 48, the function of which is to guide the pile warps into loop formations as 40 they are being embodied in the fabric H.

The front and back wefts D and E consist of two single continuous yarns, which are supplied from bobbins 49 and 50 mounted on fixtures 51 and 52 extending between the frames 18 and 19. The wefts D, E are respectively led to two reciprocating guide-spouts 53, 54, the function of 45 which is to place the wefts across the fell of the fabric in the production thereof.

The stitching threads F, G are led in separate 50 webs or sheets from two beams 55, 56 journalled at their ends in bearings on the frames 18 and 19, the threads passing from their respective beams to stitch-tightening devices, hereinafter described. The threads pass from the aforesaid 55 devices to two rows of guide fingers 57, 58 (see Fig. 4) the function of which is to lead the threads in timed sequence into operative engagement with a row of horizontal hook-needles 59 acting to knit pairs of the threads F, G into independent 60 chains of stitches which bind the wefts of one sheet to the wefts of the other sheet, thereby forming the essential structure of the fabric.

When the aforesaid guide-tubes 47, 48 guide the pile warps B, C into loop formation, they 65 form them around vertical stationary hooks 60 arranged in a row, and the newly made loops are cut by vertically reciprocating knives 61 in a manner hereinafter described.

The fabric H passes from the breast-beam 42 70 partially around a take-up beam 62 secured to the slow intermittent shaft 29 and formed with an external surface which bites into, or otherwise frictionally engages with, the fabric H, thereby imparting to it the requisite pull. The 75

fabric passes from the take-up beam 62 over guide beams 63 to a cloth beam 64 supported at opposite ends and rotated by any suitable means (not shown) to wind up the fabric at the same rate as it is produced.

The mechanism for and method of supplying the wefts D, E will now be described.

As aforesaid, the wefts are led singly to the fabric by way of two guide spouts 53 and 54. 10 As shown best in Figs. 4 and 5, the spout 53 is secured to the end of an arm 70 provided with yarn guides 71 and secured to a reciprocatory carriage 72, which is slidably mounted on a bar 73 secured at its ends to fixtures 74 on the frames 15 18 and 19. The carriage 72 co-operates with two sets of picker mechanism, which are illustrated in Fig. 5, the respective sets being supported on the frames 18 and 19 and deriving their action from the previously mentioned half-speed shaft 20 27. The two sets of picker mechanism comprise levers 75, 76, which are fulcrumed to fixtures 71 on the frames 18, 19 and which carry rollers 78, 79 acting as followers to actuating cams 80, 81. The respective levers 75, 76 are strongly pulled 25 by springs 82, 83 anchored to fixtures 84, 85 on the frames 18, 19. The respective actuating cams 80, 81 are secured to shafts 86, 87, which are driven in opposite directions and at half the speed of the main shaft 20 by two pairs of gear-wheels 88, 30 89, one wheel of each pair being secured to the shaft 27 and the other wheels being secured to the shafts 86, 87, respectively.

The other guide spout 54 is secured to the end of an arm 90 provided with yarn guides 91 and secured to a reciprocatory carriage 92, the latter being slidably mounted upon a bar 93 which is secured at its ends to the fixtures 74. The carriage 92, like the carriage 72, is operated by two sets of picker mechanism of the same construction as those already described, including two actuating cams 94, 95 secured to the shafts 86, 87 but arranged 180° out of phase with reference to the corresponding cams 80, 81.

Assuming the parts to be operating and instantaneously occupying the positions in which they are shown in Fig. 5, as the shaft 86 continues its counter-clockwise rotation, the "drop" shown in the cam 80 moves beyond the follower 78, with the result that the spring 82 forces the 45 lever 75 to turn sharply around its fulcrum and force the carriage 72 to move towards the right along the rail 73. The carriage 72 continues its movement until brought to rest by the lever 76, the shock of bringing the carriage to rest being 50 absorbed by the spring 83. At the instant when the carriage 72 is projected to the right, the carriage 92 is also projected by its picker mechanism, including the cam 95, along the rail 93, but towards the left.

55 Thus, each time the picker levers are actuated, the two carriages 72, 92 are projected in opposite directions along their rails 73, 93, and accordingly two lengths of weft D, E are simultaneously placed by the spouts 53, 54 at opposite sides of the fabric-production zone in readiness for incorporation in the fabric being there produced. The lengths of weft thus supplied are accordingly placed at opposite sides of the stuffer warps A and at the backs of (i. e. below) the 60 hook-needles 59.

The mechanism for and method of forming stitches in the threads F, G will now be described.

Referring to the previously mentioned rows of thread-guide fingers 57, 58 (Figs. 4 and 9), these 65 rows are respectively mounted on pillar bars 100,

101, there being in each row as many guide fingers as there are hook-needles 59.

The pillar bars 100 and 101 are supported at their ends in well known manner so as to be slideable across the machine endwise (i. e. so as to be capable of having imparted to them "shogging" movements), the means of support comprising brackets 102, 103 rigidly attached to segmental members, one of which is indicated by 104 in Fig. 1, these members being rigidly attached to opposite ends of a square shaft 105. This square shaft 105 is journalled at its ends in pivotal arms having pivot shafts journalled in the frames 18 and 19, one pivotal arm being indicated by 106 and its pivot shaft by 107, in Fig. 1. 15

The pillar bars 100, 101 are shogged individually by two pattern chains, one of which is shown conventionally in Fig. 2, being indicated by 108. This chain 108 constitutes one of four pattern chains, which are supported by a guide roller 109 and pass around a driving drum 110 secured to the shaft 25 and formed with five toothed rings (see Fig. 3) between which the pattern chains fit in well known manner.

The four pattern chains 108 co-operate with 25 four rollers, one of which is shown at 111 in Fig. 2. Two of these rollers are carried by slideably mounted abutment members 112 and 113 against which projections on the pillar bars 100, 101 abut, the pillar bars being acted upon by 30 springs 114, 115, which serve to maintain the pillar bars in operative engagement with the respective pattern-chains, through the intermediary of the sliding abutments 112, 113 and the respective rollers 111. The arrangement is such 35 that, in the rotation of the shaft 25, the pillar bars 100, 101 can be individually shogged in such a manner that their thread-guiding fingers 57, 58 are moved a distance equivalent to the distance between two of the knitting needles 59. In 40 order to produce the chain stitch shown in Fig. 10, the pattern-chains would be so designed that the pillar bars 100, 101 are alternately shogged to the extent of one needle space, with the result that each hook produces a single and independent chain of stitches, each chain consisting of loops in the one thread drawn through loops in the other, the loops in the respective threads alternating throughout the length of the chain, which is thus self-locked against unravelling. 50

In order that the threads F, G can be looped upon the hook-needles 59, the guide fingers 57, 58 receive in addition to the above-described shogging movements, a composite movement consisting of rising and falling movements past the 55 plane of the needles 59 and movements to-and-from the needles 59.

The rising and falling movements of the guide fingers 57, 58 are obtained from a cam 120 (Fig. 1) secured to the main shaft 20. The cam 120 60 co-operates with a roller 121 carried by a lever 122, one end of which is fulcrumed at 123 and the other end of which is pivotally attached to the lower end of a link 124, whose top end is pivotally attached to one end of a link 125, the 65 other end of which is rigidly attached to one end of the square shaft 102. The arrangement is such that, once during each revolution of the main shaft 20, the link 125 rocks the square shaft 105 about the axis thereof, with the result 70 that the guide fingers 57, 58 are raised and lowered past the plane of the hook-needles 59.

The movements of the guide fingers 57, 58 to-and-from the hook needles 59 are derived from a cam 130 (Fig. 1) secured to the half-speed 75

shaft 21. The cam 130 cooperates with a roller 131 carried by an arm 132 which is secured to the pivot shaft 107 of one of the two arms 106 supporting the ends of the square shaft 105. The arrangement is such that, twice during each revolution of the shaft 21 (i. e. once during each revolution of the main shaft) the interconnected arms 132, 106 are rocked, with the result that the pillar-bars 100, 101 and guide-fingers 57, 58 thereon are displaced to-and-from the hook-needles 59.

The manner of constructing and supporting pillar-bars bearing rows of thread-guiding fingers and the manner of actuating said bars by cams and pattern-chains are well known to those familiar with warp-knitting machines, and accordingly they need not be described or illustrated in greater detail.

The hook needles 59, in the construction illustrated, are of the type in which each cooperates with a sliding tongue or latch. In the drawings, the tongues are denoted by 140, these tongues being slidably arranged in channels formed in the needle shanks. The action of each tongue 140 relatively to the respective needle 59 is, firstly, to retire and leave the hook exposed, so that the thread F or G to be stitched can be looped around the hook; and, secondly, to advance and close upon the hook and overlap its tip, thereby providing a guide over which a previously formed loop is cast-off from the needle. Thus, in the operation of the hook needles 59, the tongues 140 move with—but differentially of—the needles.

The row of hook needles 59 are mounted on a reciprocating bar structure 142 which is secured at both ends to slideable guide-blocks, one of which is indicated by 143 in Fig. 1, the block 143 being slidably mounted on a stationary rod 144 rigidly attached to a pair of brackets 145 secured to the frame 18. The structure 142, at each end, is pivotally attached at 146 to one end of a link 147 whose other end is pivotally attached to a lever 148 fulcrumed on a stationary shaft 149. The lower end of the lever 148 carries a roller 150 which engages with a cam 151 secured to the main shaft 20. The arrangement is such that, in each rotation of the shaft 20, the lever 148 is rocked to-and-fro by the cam 151 and imparts through the link 147 a reciprocating movement to the bar structure 142 and the needles 59 thereon.

The tongues 140 are secured to a bar structure 152 which, at each end, is pivotally attached at 153 to one end of a link 154 whose other end is pivotally attached to a lever 155, which also is fulcrumed on the shaft 149. The lever 155 carries at its lower end a roller 156 engaging with a cam 157 secured to the main shaft 20. The arrangement is such that the cam 157 rocks the lever 155 once in each revolution of the main shaft 20, thereby imparting to the tongue-bar 152 and tongues 140 thereof, through the intermediary of the link 154, the requisite differential movements relatively to the hook-needles 59.

In Fig. 1, there is shown mechanism whereby the cams 151 and 157 impart reciprocating movements to those ends of the needle bar 142 and the tongue bar 152 which are in the vicinity of the frame 18; and it is to be understood that similar cams and similar mechanism would be provided at the opposite ends of the bars 142, 152, and that the said mechanism would be supported by brackets corresponding to the brackets 145 but attached to the frame 19.

It is when the needles 59 are fully advanced (i. e. moved to the left as viewed in Fig. 1) that their hooks are looped by the threads F or G under the guidance of the fingers 57, 58. Prior to this inter-action between the fingers and needles, the spouts 53, 54 have been forced to reciprocate across the machine and lay in lengths of the wefts D, E. Thus, in the formation of a stitch by the needles 59, the stitch includes a loop which embraces the two previously laid in lengths of the wefts D and E (see Fig. 10). It will be clear that, in order to render the fabric firm, it is desirable that the last-formed stitch should be pulled tight. Mechanism for pulling the threads G and F tight will now be described.

The stitch-tightening mechanism is actuated by four cams 160 to 163 secured to the half-speed shaft 21 (see Figs. 1 and 2). Referring first of all to the action of the said mechanism upon the sheet of threads F, the beam 55 on which these threads are wound is provided with a brake-drum 164 (see Fig. 1). A brake-band 165 wrapped partially around the brake-drum is anchored at one end 166 to the frame 18 and is connected at its other end, by connections 167, 25 to a lever 168, one end of which is fulcrumed at 169 on the frame 18 and the other end of which carries a roller 170 co-operating with the cam 160. The arrangement is such that, once in every revolution of the shaft 21 (i. e. once in every two revolutions of the main shaft 20), the cam 160 imparts to the lever 168 an upward motion whereby the brake-band 165 is drawn tightly against the drum 164, so that the beam 55 is temporarily locked against rotation. The 35 tightening action is applied to the threads F by a rod 171 (see Fig. 1) supported at its ends by arms, one of which is indicated by 172. These arms are secured to a shaft 173 journalled at its opposite ends in the frames 18, 19, the shaft 173 serving also as a guide for the threads F. To one end of the shaft 173 there is secured an arm 174 which carries a roller (not shown, being obscured by the roller 170 in Fig. 1) co-operating with the cam 162. The arrangement is such 45 that, at the time when the beam 55 is temporarily locked, the cam 162 imparts an upward movement to the arm 174, whereby the shaft 173 is turned counter-clockwise, with the result that the bar 171 is moved to the left and imparts a 50 pull to the sheet of threads F, thereby tightening the stitches last formed in these threads.

Referring now to the sheet of threads G, which are wound upon the beam 56, the aforesaid cams 161 and 163 respectively operate brake-mechanism and thread-pulling mechanism of the same construction as already described with reference to the threads F, and the said mechanisms have therefore been denoted in Fig. 1 by the same reference numerals. For clearness, the arm 172, and the rod 171 adapted to pull the threads G, have been shown displaced into the position which they occupy at the conclusion of the pull.

It is to be understood that arms 172, corresponding to those shown in Fig. 1, would be provided in the vicinity of the frame 19 to support the adjacent ends of the bars 171.

The mechanism for and method of leading-in the pile warps B, C will now be described.

The two rows of pile-guiding tubes 47, 48 are 70 respectively secured to tube-bars 180, 181 which are slidably attached at 182, 183 to (although held against rotation relatively to) a pair of arms 184 secured to opposite ends of a shaft 185 which is journalled at its ends in arms 186 secured to 75

a rock-shaft 187 journalled at its ends in the frames 18, 19. The tube bars 180, 181 are so supported that they receive a shogging movement, a lowering-and-raising movement, and a short rocking movement, the resultant of the three composite movements being such that the pile-guiding tubes lap the pile warps around the stationary pile-forming hooks 60.

The shogging movements of the tube bars 180, 181 are independently received from two of the four pattern chains already described, and one of which is denoted by 108 in Fig. 2. For this purpose, the tube-bars are provided at the ends thereof adjacent to the frame 19 with abutment plates which co-operate with projections on two slides provided with two of the four rollers indicated by 111 in Fig. 2; one abutment plate 190, one projection 191 and one slide 192 being shown in Fig. 2. These parts are adapted to form an operative connection between the respective roller 111 and the tube bar 180, the aforesaid connection being maintained continuous by a spring 193 anchored at 194 to the shaft 185. The tube bar 181 is operated similarly.

Thus, it will be seen that the shogging movements of the tube-bars 180, 181 are derived in the same manner as the shogging movements of the pillar bars 100, 101.

Moreover, the extents by which the tube-bars 180, 181 are shogged can be varied under the control of the pattern-chains to produce pattern effects in the pile.

The lowering-and-raising movement of the tube-bars 180, 181 is derived from a cam 201 (see Fig. 3) secured to the main shaft 20. This cam co-operates with a roller 202 carried by a lever 203, one end of which is fulcrumed at 204 and the other end of which is connected by a link 205 to an extension 206 of one of the two arms 186. The arrangement is such that, during each rotation of the shaft 20, the cam 201 imparts a rocking movement to the lever 203, with the result that the tubes 47, 48, in unison, are lowered below the level of the hooks 60 and thereafter raised above said level again.

The rocking movement of the tube-bars 180, 181 is derived from a cam 210 on the shaft 20. This cam co-operates with a roller 211 carried at the lower end of a lever 212, which is fulcrumed at 213 and the top end of which is connected by a link 214 to an extension 215 of one of the two arms 184. The arrangement is such that, once during each revolution of the shaft 20, the lever 212 is rocked by the cam 211, with the result that the tubes 47, 48, in unison, are rocked to-and-fro past the hooks.

In the construction illustrated, there are only two rows of guide-tubes, and it is to be understood that the machine may have more than two rows if required, more particularly if the machine is intended to produce variously patterned fabrics.

Referring again to the rows of thread-guiding fingers 51, 58, and to the fact that the guide-tubes 47, 48 may move amongst them during the operation of lapping the pile threads around the hooks 60, the pattern-chains 108 controlling the shogging movements of the fingers must under such circumstances be designed to impart an auxiliary shogging movement to the fingers, when the tubes are being shogged, to avoid fouling between the fingers and tubes.

The mechanism for and method of cutting the loops in the pile threads B, C will now be described, more particularly with reference to Figs.

6 to 8 in which the said mechanism is most clearly shown.

The knives 61 consist of thin blades which are arranged to slide in grooves 220 formed in the loop-forming hooks 60 (see also Fig. 9), so that these hooks present the appearance of sheath-like members serving as partial guides for the knives. The hooks 60 are secured to a bar structure 221 serving also to guide the knives and supported at its ends by brackets 222 on the frames 18 and 19 (see also Fig. 1). The top end of each knife is formed as a sharp inclined edge which works immediately below the loop-forming hooks, while the bottom of each knife is formed with an eyelet 223 through which passes a removable pin 224 extending at both ends between the vertical dents 225 of a double stationary reed and projecting into the path of a double sliding cam 226, having upwardly and downwardly inclined cam grooves 227. The dents 225 serve for vertical guidance of the pins 224, whereas the cam grooves 227 serve as a means for raising the knives from their lowermost position. There are several double cams 226, all arranged to slide as a gang on stationary horizontal bars 228 supported at their ends on brackets 229 on the frames 18 and 19 (see also Fig. 1), the cams being interconnected to slide in unison by links 230. The cams receive a continuous reciprocatory motion from an eccentric 231 secured to the shaft 20.

Moreover, the eccentric 231 imparts the necessary movement through an articulated train comprising an eccentric rod 23, a bell-crank-lever 233 fulcrumed at 234 on the frame 19, a link 235 and a lever 236, which is fulcrumed at 237 on a bracket 238. The lever 236 has a sliding connection at 239 with the endmost double cam 226.

The arrangement is such that, during the operation of the machine, the cams slide in unison to-and-fro along the bar 228 and impart a vertical cutting motion to the knives in sequence, which therefore cut whatever loops of pile embrace the shanks of the hooks. The sequential action obviates shock, and since the pile-cutting operation is uniformly distributed over the complete cycle, the minimum power for cutting is expended.

The above-mentioned feature permits high speeds to be attained, especially owing to the fact that the hooks, being stationary, do not have to slide to-and-fro through initially uncut loops, thereby keeping the resistance of the pile-looping-and-cutting mechanism low.

Any knife-blade can be conveniently removed simply by withdrawing its bottom pin 224 and allowing the blade to drop out of its hook shank.

With reference to the machine in its entirety, the working parts are so timed in relation to each other that the following cycle of operations takes place during each revolution of the main shaft 20, it being assumed that a portion of fabric H has already been produced.

Two lengths of weft D, E are simultaneously placed across the top of the fabric by the spouts 53, 54. The thread D is led-in at the pile side 65 of the sheet of stuffer warps A and rests against the stuffer warps, the threads F, G extending from the fingers 51, 58, and the last-formed loops in the pile warps B or C. The thread E is led-in at the ground side of the sheet of stuffer warps 70 A and rests against these warps and also loops extending to the hook needles 59.

The hook-needs 59 advance across the tops of the wefts D, E and pass through and beyond the sheets of warps A, C and B. The 75

tongues 140 also advance, but to a lesser extent than the needles 59, whose hooks are therefore fully exposed. One of the two rows of guide-fingers, say the fingers 57, receive the composite 5 thread-looping movement hereinbefore described, and accordingly loop the threads F upon the exposed hooks of the needles 59.

The needles 59 are retracted through the sheets of warps, the needles carrying with them the 10 engaged threads F. Meantime the tongues 140 relatively advance to overlie the hook tips, and the needles 59 and tongues 140 are withdrawn, so that the last-formed loops in the threads G are cast-off, thereby producing stitches. These 15 stitches include loops (newly formed by the retiring needles 59) in the threads F, which loops embrace the wefts D, E and hold them against the warps A, B and C. The stitch-tightening mechanism provided for the threads G is now 20 actuated, the respective drum 164 being braked and the respective rod 171 being displaced to pull on the sheet of threads G in the manner hereinbefore described. Accordingly, the cast-off loops in the threads G are pulled tight, with 25 the result that the wefts embraced by these cast-off loops are drawn tightly into the fabric. However, the loops last formed in the threads F and still engaged by the needles 59 receive no pull whatever, so that the wefts embraced by these 30 loops are merely held thereby lightly in place at this stage. The fact that the wefts are drawn tightly into the fabric at a time when the threads binding them are entirely free from the needles 59 ensures that the fabric can be very tight and 35 compact and yet the knitting speed is not reduced.

The rows of tubes 47, 48 pass below the tips of the hooks 60, and that row which is operated by its pattern-chain 108 performs a looping movement around the hooks, whereby the pile warps comprising one or other of the sheets B, C are lapped around the hooks 60 in readiness to be bound in place during the succeeding cycle of operations. In said succeeding cycle, however, 40 it is the threads G which are looped by their guide fingers 58 upon the hooked-needles 59 and it is the loops formed in the threads during the preceding cycle which are cast-off and pulled tight.

Throughout the cycle, as previously explained, 45 the pile-cutting operation continuously takes place.

The fabric produced may be of the simple form 50 illustrated in Fig. 10. As will be gathered therefrom, the threads F, G are formed into single 55 independent chains which extend lengthwise between adjacent groups of stuffer and pile warps A, B and C, and which serve to bind the wefts D, E and stuffer warps A into the form of a strong fabric structure serving as the ground 60 of the complete cut-pile fabric in the example described. It will be observed that the pile loops are not "knitted-in"—that is to say, they are not 65 acted upon at all by the hook-needles 59—and that they are held in place solely by the front wefts D, below which they pass.

With reference now to the manufacture of 70 looped pile fabrics, a portion of a machine for producing such fabrics is shown in Fig. 11. Except for certain of the parts therein shown and now to be described, this machine may be identical with the machine already described with reference to Figs. 1 to 9, but with the fixed 75 loop-forming hooks and the pile-cutting knives and their operating means removed.

Referring to Fig. 11, the pile-guiding tubes 47, 48, thread-guiding fingers 57, 58, hook needles 59, and the take-up beam 62 are all the same as previously described. The stationary breast-beam 300 is hollowed out to accommodate a roller 301 around which the fabric passes to the take-up beams 62, the roller 301 being journalled at its ends so as to be freely rotatable. A row of floating loop-forming hooks 302, with curved shanks 303 serving as guides for the looped pile fabric 10 as it passes to the roller 301, are provided in association with a toothed bridge, shown also in Figs. 12, 13 and 14. The bridge 304 extends across the machine and is supported at its ends by brackets, one of which is indicated by 305. Each 15 of these brackets is adjustably secured by a screw 306 to a cam-rod 307, which is vertically slidable in guides 308 on a stationary bracket 309. The cam-rod 307 has at its lower end a roller 310 which rides upon a cam 311 secured to a cam-shaft 312 20 driven by, and at the same speed as, the main-shaft of the machine (i. e. the shaft 20 described with reference to Figs. 1 to 9) through the intermediary of any suitable gearing (not shown).

The arrangement is such that, in the normal 25 operation of the machine, the hooks 302 are supported by the loops formed in the pile threads, as shown in Figs. 12 and 13, the action of the bridge 304 being to rise and engage the hooks once during 30 each cycle of operations (see Figs. 11, 12 and 14) and position them accurately in the spaces between its teeth. While the looping operation is being performed, the bridge 304 is lowered out of the way, as shown in Fig. 13, the thread-guiding fingers being at the same time withdrawn clear of 35 the pile tubes.

The fabric K shown in Figs. 12 and 13 has been 40 illustrated conventionally, for clearness. This fabric may be the same as that diagrammatically illustrated in Fig. 10, except that the pile warps B, C are not cut.

At the commencement of fabric-production, there being no pile loops to support the floating 45 hooks 302, 303, the latter are set up, away from the machine, in a cradle 313, a portion of which is shown in Figs. 15 to 17. This cradle is formed in its convex face with grooves 314 into which the hook shanks 303 can be neatly seated, as shown in Fig. 17. When the hooks are thus set up, a wire 50 315 is strung from end-to-end of the cradle, thereby locking the hooks in place.

The machine is first of all operated to produce a short length of unlooped fabric, a bridge 304 being temporarily removed. Then the loaded cradle 313 is positioned temporarily in place in 55 the machine, and the latter is manipulated slowly by hand until sufficient loops are formed upon the hooks to support them. Then the cradle is removed, and the bridge is replaced.

Obviously, a single cradle can be utilized for 60 several machines in turn.

If desired, the parts herein described with reference to Figs. 11 to 17 may be interchangeable with the parts to which they correspond in the machine described with reference to Figs. 1 to 9, 65 so that the one machine may be quickly and conveniently convertible for manufacturing different kinds of fabric. Thus, the machine can be utilized to manufacture a large variety of fabrics, namely 70 cut-pile, looped pile, and simple non-pile fabrics composed of warps and wefts bound together by stitching, as distinguished from inter-weaving; and that the fabrics produced can be patterned, striped or plain. If desired, a patterned pile sur- 75

face could be obtained by dispensing with all loop-forming mechanism and supplying strips of chenille as wefts in lieu of or in addition to the wefts D.

5. The particular kind of knitting needles described and illustrated is preferred for high speed working; but ordinary latch-needles, or other suitable kind may be used if desired.

I claim:—

10. 1. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile sheets, mechanism for producing chains of stitches which extend along spaces between groups of said stuffer and pile warps and inter-bind the wefts, stationary hooks around which the weft-bound pile warps are looped during said pile-looping movements, knives provided in combination with said hooks, and means for moving said knives to cut the looped pile warps.

20. 2. A fabric manufacturing machine adapted to receive a sheet of stuffer warps and comprising guides for leading-in a sheet of pile warps, mechanism for imparting looping movements to said guides, means for supplying wefts to opposite faces of said stuffer and pile sheets, and mechanism for producing chains of stitches which extend along spaces between groups of said stuffer and pile warps and inter-bind the wefts, stationary hooks around which the weft-bound pile warps are looped during said pile-looping movements, knives slidably mounted in combination with said hooks, and means for sliding said knives in sequence to cut the looped pile warps.

30. 3. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile sheets, and mechanism for producing chains of stitches which extend along spaces between groups of said stuffer and weft-bound pile warps and inter-bind the wefts, stationary hooks around which the pile warps are looped, knives slidably mounted on said hooks, projections on said knives, stationary guides for said projections, cam means engageable with said projections, and means for reciprocating said cam means so as to slide said knives in sequence and thereby cut the looped pile warps.

40. 4. A fabric manufacturing machine adapted to receive a sheet of stuffer warps and comprising guides for leading-in a sheet of pile warps, mechanism for imparting pile-looping movements to said guides, weft-receiving guides mounted at opposite faces of the associated sheets of stuffer and pile warps, mechanism for reciprocating said guides to place wefts across said opposite faces, and mechanism for producing chains of stitches which extend along spaces between groups of said stuffer and pile warps and inter-bind the wefts, which thus bind the warps.

50. 5. A fabric manufacturing machine adapted to receive a sheet of stuffer warps and comprising guides for leading-in a sheet of pile warps, mechanism for imparting pile-looping movements to said guides, weft-receiving guides mounted at opposite faces of the associated sheets of stuffer and pile warps, mechanism for reciprocating said guides to place wefts across said opposite faces, mechanism for producing

chains of stitches which extend along spaces between groups of said stuffer and pile warps and inter-bind the wefts, stationary hooks around which the weft-bound pile warps are looped during said pile-looping movements, knives provided in combination with said hooks, and means for moving said knives to cut the looped pile warps.

6. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile warp sheets, mechanism for producing chains of stitches which extend along spaces between said warps and inter-bind the wefts, and floating hooks around which the pile warps are looped during said pile-looping movements, said floating hooks being normally supported by the looped pile warps.

7. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile warp sheets, mechanism for producing chains of stitches which extend lengthwise of said warps and inter-bind the wefts, floating hooks around which the pile warps are looped during said pile-looping movements, said floating hooks being normally supported by the looped pile warps, a bridge movably mounted in the vicinity of the position occupied by said floating hooks, and means for moving said bridge at timed intervals to engage the floating hooks and position them for said pile-looping movements.

8. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile warp sheets, a rotatable beam serving for the supply of binding threads, mechanism for producing chains of stitches which extend along spaces between said warps and inter-bind the wefts, brake means for holding said beam against rotation at timed intervals, tightening means associated with said binding threads, means operable at said intervals to displace said tightening means and thereby tighten the stitches, and floating hooks around which the pile warps are looped during said pile-looping movements, said floating hooks being normally supported by the looped pile warps.

9. A method of manufacturing fabrics which consists in supplying wefts to the opposite faces of a sheet of warps spaced apart, producing in two sets of threads chains of stitches along the spaces between the warps to interbind the wefts, each chain consisting of the same two alternately looped threads belonging to the respective sets, and pulling a set of said threads to tighten already formed weft-binding stitches while the other set of threads are in condition for formation into fresh stitches.

10. A method of manufacturing fabrics which consists in supplying wefts to the opposite faces of a sheet of warps spaced apart, supplying two sets of binding threads, producing therein chains of stitches along the spaces between the warps to inter-bind the wefts, each chain consisting of the same two alternately looped threads, alter-

- nately restraining the supply of the respective sets of threads and pulling the restrained threads to tighten the stitches.
11. A method of manufacturing pile fabrics which consists in supplying wefts to the front and back faces of a sheet composed of stuffer warps and pile warps, producing chains of stitches to extend along spaces between the warps to inter-bind the wefts, and forming loops in the pile warps, said loops being bound by the front wefts.
12. A method of manufacturing pile fabrics which consists in supplying wefts to the front and back faces of a sheet composed of stuffer warps and pile warps spaced apart in groups, producing chains of stitches along the spaces between the groups of warps to inter-bind the wefts, and forming loops in the pile warps, which loops are bound by the front wefts.
13. A method of manufacturing pile fabrics which consists in supplying wefts to the front and back faces of a sheet composed of stuffer warps and pile warps spaced apart in groups, producing chains of stitches along the spaces between the groups of warps to inter-bind the wefts, forming loops in the pile warps, which loops are bound by the front wefts, and cutting said loops to form a cut-pile surface.
14. A method of manufacturing pile fabrics which consists in supplying wefts to the front and back faces of a sheet composed of stuffer warps and pile warps spaced apart in groups, supplying binding threads, producing therein chains of stitches along the spaces between the groups of warps to inter-bind the wefts, forming loops in the pile warps, which loops are bound by the front wefts, periodically restraining the supply of said threads, and pulling said threads to tighten the stitches.
15. A method of manufacturing pile fabrics which consists in supplying wefts to the front and back faces of a sheet composed of stuffer warps and pile warps spaced apart in groups, supplying two sets of binding threads, producing with said threads chains of stitches along the spaces between the groups of warps to inter-bind the wefts, each of said stitches consisting of a loop in a thread of one set drawn through a loop in a thread of the other set, and forming loops in the pile warps, which loops are bound by the front wefts.
16. In a method of manufacturing pile fabrics according to the last preceding claim, alternately restraining the supply of the respective sets of binding threads and pulling the restrained threads to tighten the stitches produced therein.
17. A fabric manufacturing machine adapted to receive a sheet of spaced warps and comprising weft-receiving guides mounted at opposite faces of the sheet of warps, mechanism for reciprocating said guides to place wefts across said opposite faces, mechanism for producing from two sets of threads chains of stitches which extend along the spaces between said warps and inter-bind the wefts, each chain consisting of the same two alternately looped threads belonging to the respective sets, and two alternately operating stitch-tightening devices, each operating to pull a set of said threads and so tighten already formed weft-binding stitches while the other set of said threads are in condition for formation into fresh stitches.
18. A fabric manufacturing machine adapted to receive a sheet of spaced warps and comprising means for supplying wefts to opposite faces of said sheet of warps, rotatable beams serving for the supply of two sets of binding threads, mechanism for producing with said threads chains of stitches which extend along the spaces between said warps and inter-bind the wefts, each chain consisting of the same two alternately looped threads, brake means for holding the respective beams against rotation at timed intervals, tightening means associated with said binding threads, and means operable at said intervals to displace said tightening means and thereby tighten the stitches in the respective sets of threads.
19. A fabric manufacturing machine adapted to receive a sheet of spaced warps and comprising weft-receiving guides mounted at opposite faces of the sheet of warps, mechanism for reciprocating said guides to place wefts across said opposite faces, rotatable beams serving for the supply of two sets of binding threads, mechanism for producing with said threads chains of stitches which extend along the spaces between said warps and inter-bind the wefts, each chain consisting of the same two alternately looped threads, brake means for holding the respective beams against rotation at timed intervals, tightening means associated with said binding threads, and means operable at said intervals to displace said tightening means and thereby tighten the stitches in the respective sets of threads.
20. A fabric manufacturing machine adapted to receive a sheet of stuffer warps and comprising guides for leading-in a sheet of pile warps, mechanism for imparting pile-looping movements to said guides, means for supplying wefts to opposite faces of said stuffer and pile sheets, and mechanism for producing chains of stitches which extend lengthwise between said warps and inter-bind the wefts, which thus bind the warps, the respective chains consisting of the same threads throughout their length.
21. A fabric manufacturing machine adapted to receive a sheet of stuffer warps and comprising guides for leading-in a sheet of pile warps, mechanism for imparting looping movements to said guides, means for supplying wefts to opposite faces of said stuffer and pile sheets, rotatable beams serving for the supply of two sets of binding threads, mechanism for producing with said threads chains of stitches which extend along spaces between groups of said stuffer and pile warps and inter-bind the wefts, each of said chains consisting of the same two alternately looped threads, brake means for holding the respective beams against rotation at timed intervals, tightening means associated with said sets of binding threads, and means operable at said intervals to displace said tightening means and thereby tighten the stitches in the respective sets of threads.
22. A fabric manufacturing machine adapted to receive a sheet of stuffer warps and comprising guides for leading-in a sheet of pile warps, mechanism for imparting looping movements to said guides, means for supplying wefts to opposite faces of said stuffer and pile sheets, rotatable beams serving for the supply of two sets of binding threads, mechanism for producing with said threads chains of stitches which extend along spaces between groups of said stuffer and pile warps and inter-bind the wefts, each of said chains consisting of the same two alternately looped threads, brake means for holding the respective beams against rotation at timed intervals, tightening means associated with said sets of binding threads.

of binding threads, and means operable at said intervals to displace said tightening means and thereby tighten the stitches in the respective sets of threads, stationary hooks around which the 5 weft-bound pile warps are looped during said pile-looping movements, knives slidably mounted in combination with said hooks, and means for sliding said knives in sequence to cut the looped pile warps.

10 23. A fabric manufacturing machine adapted to receive a sheet of stuffer warps and comprising guides for leading-in a sheet of pile warps, mechanism for imparting pile-looping movements to said guides, weft-receiving guides mounted at 15 opposite faces of the associated sheets of stuffer and pile warps, mechanism for reciprocating said guides to place wefts across said opposite faces, rotatable beams serving for the supply of two sets of binding threads, mechanism for producing 20 with said threads chains of stitches which extend along spaces between groups of said stuffer and pile warps and inter-bind the wefts, each of said chains consisting of the same two alternately looped threads, brake means for holding the 25 respective beams against rotation at timed intervals, tightening means associated with said sets of binding threads, means operable at said intervals to displace said tightening means and thereby tighten the stitches in the respective sets 30 of threads, stationary hooks around which the weft-bound pile warps are looped during said pile-looping movements, knives slidably mounted in combination with said hooks, and means for sliding said knives in sequence to cut the looped pile 35 warps.

24. A method of manufacturing fabrics which comprises the operations of supplying front and back wefts to the opposite faces of a sheet of warps, producing chains of stitches to extend 40 along spaces between the warps and interbind the front and back wefts, and forming loops in the warps, said loops projecting between and being bound by the front wefts.

25. A method of manufacturing fabrics which 45 comprises the operations of supplying front and back wefts to the opposite faces of a sheet of warps, producing in two sets of threads chains of stitches to extend along spaces between the warps and interbind the front and back wefts, each 50 chain consisting of the same two alternately looped threads belonging to the respective sets, forming loops in the warps, said loops projecting between and being bound by the front wefts, and pulling a set of said threads to tighten already 55 formed weft-binding stitches while the other set of threads are in condition for formation into fresh stitches.

26. A method of manufacturing fabrics which comprises the operation of supplying wefts to the opposite faces of a sheet composed of stuffer warps and pile warps spaced apart in groups, producing 5 in two sets of threads chains of stitches along the spaces between the groups of warps to interbind the wefts, each chain consisting of the same two alternately looped threads belonging to the respective sets, forming loops in the pile warps, which loops are bound by the front wefts, and 10 pulling a set of said threads to tighten already formed weft-binding stitches while the other set of threads are in condition for formation into fresh stitches.

27. A fabric manufacturing machine adapted 15 to receive a sheet of warps and comprising means for supplying front and back wefts to opposite faces of said sheet of warps, mechanism for producing chains of stitches which extend along spaces between said warps and inter-bind the 20 front and back wefts, and means for forming loops in the warps, said loops projecting between and being held in place by the front wefts.

28. A fabric manufacturing machine adapted 25 to receive a sheet of warps and comprising means for supplying front and back wefts to opposite faces of said sheet of warps, mechanism for producing chains of stitches which extend along spaces between said warps and inter-bind the front and back wefts, means for forming loops in 30 the warps, said loops projecting between and being held in place by the front wefts, and means for cutting said loops.

29. A fabric manufacturing machine adapted 35 to receive a sheet of warps and comprising means for supplying front and back wefts to opposite faces of said sheet of warps, mechanism for producing in two sets of threads chains of stitches which extend along spaces between said warps and inter-bind the front and back wefts, each 40 chain consisting of the same two alternately looped threads belonging to the respective sets, means for forming loops in the warps, said loops projecting between and being held in place by the front wefts, and two alternately operating stitch-tightening devices, each operating to pull a set of said threads and so tighten already formed 45 weft-binding stitches while the other set of said threads are in condition for formation into fresh stitches.

30. A fabric manufacturing machine according 50 to the last preceding claim and having in combination with the parts therein defined means for cutting said loops.

JAMES MORTON.
